UNITED STATES PATENT OFFICE.

GROVER C. HILL AND JAMES H. TAYLOR, OF OWENSBORO, KENTUCKY.

GRADER.

Application filed June 17, 1924. Serial No. 720,578.

To all whom it may concern:

Be it known that we, GROVER C. HILL and JAMES H. TAYLOR, citizens of the United States, residing at Owensboro, in the county of Daviess and State of Kentucky, have invented certain new and useful Improvements in Graders, of which the following is a specification.

This invention relates to grading and ditching machines and seeks to improve the construction of such machines to the end that the durability thereof may be increased and the cost of production and maintenance reduced. The invention also seeks to provide an improved construction whereby the blade will be braced when the machine is in use and may be easily adjusted so that its front end will enter the ground to a greater or less depth as may be desired and also permit the blade to be easily reversed when it is desired to direct all the loosened dirt to one side of a road or ditch. Other objects of the invention will appear incidentally in the course of the following description, and the invention resides in certain novel features which will be hereinafter first fully described and then more particularly pointed out in the appended claims.

In the accompanying drawings, which illustrate one embodiment of our invention,

Figure 1 is a plan view of our improved grader;

Fig. 2 is a front elevation;

Fig. 3 is a section on the line 3—3 of Fig. 1;

Fig. 4 is a detail section on the line 4—4 of Fig. 1, and

Fig. 5 is a detail section on the line 5—5 of Fig. 1.

Fig. 6 is a detail side elevation of an end of the landside.

Briefly stated, the grader consists of a landside, a blade, suitable connections between the blade and the landside, and means for applying draft to the landside. The landside is constructed of two angle bars having their vertical webs 1 disposed in the same plane, as shown most clearly in Fig. 5, and having their horizontal webs 2 dis-

posed in abutting relation, rivets or similar fastenings, indicated at 3, being inserted through the horizontal webs whereby to secure the same rigidly together. The horizontal webs are cut away at points short of the ends of the vertical webs, as shown in Fig. 1, and the ends of these horizontal webs

are disposed obliquely, as shown at 4, so that they will not interfere with the angular disposition of the blade. The horizontal webs constitute a platform or foot rail to support the driver of the machine and they are provided adjacent their free longitudinal edges with openings 5, the purpose of which will presently appear. Adjacent the ends of the landside, I secure to the inner side thereof yokes or brackets 6 which, as shown most clearly in Fig. 4, are substantially U-shaped having vertical webs or bodies secured rigidly against the vertical webs of the landside and bridging the joint between the same while at the upper and lower ends of the said vertical webs are laterally directed lugs 7 having longitudinal slots 8 therethrough. We also secure to the ends of the landside brackets 9 which consist substantially of metallic straps doubled upon themselves and having the leaves thus produced riveted or otherwise rigidly secured to the opposite sides of the landside at the ends thereof, the bight or fold between the plies being disposed beyond the extremities of the landside, as shown in Figs. 1 and 2. The bight or fold of each of these brackets is notched, as indicated at 10, thereby defining upper and lower hinge eyes 11, as clearly shown, and, if desired, the inner sides of the brackets may be provided with beveled recesses or notches 12 in their lower edge portions to accommodate possible extreme adjustment of the front end of the blade and avoid choking and accumulation of dirt between the blade and the bracket. We also employ a clevis 13 which is provided with a vertical series of openings 14 in any one of which a draft chain or similar device may be engaged, and this clevis includes a series of three rearwardly projecting eyes 15 which are adapted to engage between the eyes 11 and above and below the same, as shown in Fig. 2, a king bolt 16 being inserted through the vertically aligned eyes whereby to couple the clevis to the bracket. Obviously, the clevis and the draft devices connected therewith may be arranged at either end of the landside and coupled to either draft bracket 9 according to the direction in which the machine is to be hauled.

The blade 17 consists of a steel plate having a concave front face and having its ends disposed upon oblique lines, as shown at 18, whereby the end edges of the blade

will converge upwardly and the lower corners of the blade will be adapted to cut readily into the ground, thereby eliminating the use of plows or other breaking implements when new ground is to be graded. Upon the rear side of the blade immediately adjacent each end thereof, we provide a coupling rib or bracket 19 which extends vertically of the blade and may be produced by riveting or otherwise rigidly securing to the blade angle bars curved longitudinally from end to end to correspond to the curvature of the blade and having their rearwardly projecting webs placed together, as shown, a plurality of openings 20 being formed through the said webs. The connection between the end of the blade and the landside also includes a coupling yoke 21 which spans the bracing and coupling rib 19 and is pivotally attached thereto by a bolt 22 inserted horizontally through the ends of the yoke and one of the openings 20 in the rib, the relatively vertical location of the end of the blade being determined by selecting the proper opening 20 in which to engage the coupling pivot bolt. The outer or rear end of the coupling yoke 21 fits between the lugs 7 of the brackets 6 and defines a vertically disposed sleeve or eye 23 through which a coupling bolt 24 is engaged. The said bolt 24 passes through the slots 8 in the bracket 6 and may obviously be shifted along the said slots so as to accommodate varying angular positions of the blade.

Disposed longitudinally upon the rear side of the blade approximately midway the height thereof, we secure an angle bar 25 which serves to reinforce the blade and also constitutes a foot rest so that the driver by standing upon the said foot rest and the platform 2 will add his weight to the machine to hold it to its work and may very easily control the draft team. The hand rails which have been frequently used are unnecessary with our device and as they frequently interfere with the movements of the driver, they have been eliminated. The driver may very readily brace himself against the blade and the landside so that he is not apt to suffer injury in the normal operation of the machine. Rigidly secured to the back of the blade at the center thereof is a bracket 26 having rearwardly projecting lugs 27 at its upper and lower ends. A bracing yoke 28 has its ends disposed between the lugs 27 and coupled thereto by a pivot bolt 29 inserted through the said lugs and the ends of the bracing yoke, as shown clearly in Fig. 3. It will be readily noted that the bracing yoke 28 is substantially V-shaped with its sides converging rearwardly from its ends and connected by a head or bridge member 30. A fork 31 is engaged over the edges of the horizontal

webs 2 of the landside and a coupling pivot bolt 32 is inserted vertically through the rear ends of the fork and through one of the openings 5 so that the fork will be attached to the foot rail and may be swung pivotally forwardly or rearwardly as may be desired. The outer end of the fork 31 is constructed with a stud 33 passing horizontally through a central opening provided therefor in the head 30 of the bracing yoke 28 so that the bracing yoke may have pivotal movement upon the fork. The stud 33 is threaded through a portion of its length and the threaded portion is engaged by a nut 34 whereby the fork and the bracing yoke will be held in operative relation.

We also provide guide runners 36 which are riveted or otherwise fixed to the outer side of the landside and project below the lower edge thereof so as to enter the ground and hold the machine to a rectilinear path, the labor of guiding the machine being thus minimized. By disposing these guide runners upon the outer side of the landside, they perform their functions more effectually than if they were upon the inner side as is the more general practice and also are disposed so that they will not interfere with the action of the blade.

In Fig. 1, we have shown the device arranged for work. Draft is applied through the chain 35 to the front end of the landside and the machine is thereby drawn forward so that the blade will cut into the surface of the ground and reduce the same to a level, the surplus loose dirt being deflected to one side and escaping at the rear or outer end of the blade. When the machine has been drawn to the limit of the operations, it is not necessary to turn the entire machine around inasmuch as the blade may be simply reversed by removing the coupling bolt 24 and the yoke 21 from the front end of the blade and the landside and connecting them to the rear ends of the blade and landside, the blade being swung pivotally about the bolt 32, as will be readily understood upon reference to the dotted lines in Fig. 1. The draft devices are, of course, shifted to the rear end of the landside and the machine may then be drawn backward over the same path or in a parallel path so that the loose dirt will be all turned to the same side of the road or ditch. The central connection between the blade and the landside consisting of the bracket 26, the yoke 28 and the fork 31 very effectually holds the blade to its work and resists bending or buckling thereof whether the machine be drawn in one or the opposite direction, and the angular position of the blade may be readily varied by shifting the pivot bolt 32 to one or another of the openings 5, the pivotal shifting of the end of the blade being accommodated by the sleeve 23 turning about the

bolt 24 as a pivot. The bolt 24 may be shifted longitudinally of the slots 8 so as to further accommodate the different positions of the blade, and this simple construction provides for a very wide adjustment of the blade. It is also possible to adjust the blade pivotally about the pivot bolt 29 so that the range of adjustment is thereby increased. By engaging the bolt 22 in one or another opening 20, the front end or point of the blade may be set to cut at a greater or less depth, and this adjustment of the blade will be accommodated by the pivotal movement of the yoke 28 about the stud 33 so that re-
15 adjustment of the bracing yoke or any other member of the central connection between the blade and the landside is unnecessary. The particular construction of the landside produces a member of great strength and durability at a very slight expense. The particular construction of the clevis is very advantageous inasmuch as the pulling strain is thereby distributed to three points upon the king bolt so that bending of the king bolt
25 is avoided and the pulling force is so exerted as to very quickly set the device in motion. The machine presents simplicity of construction combined with great strength and durability so that the cost of production is
30 comparatively low.

Having thus described the invention, we claim:

1. In a grader, the combination of a blade, a landside, a vertically extending rib upon the rear side of the blade at the end thereof, a bracket secured upon the landside, and a coupling yoke connected to the bracket by a vertical pivot and to the said rib by a horizontal pivot.
2. In a grader, the combination of a blade, a landside, a vertically disposed rib on the rear side of the blade at the end thereof, said rib having a plurality of horizontal openings therethrough, a bracket secured to the landside adjacent the end thereof, a coupling yoke comprising a sleeve engaged with the said bracket and end members disposed at opposite sides of said rib, a vertically disposed pivot bolt extending through the bracket and the said sleeve, and a horizontally disposed pivot bolt extended through the end members of the yoke and through one of the openings in the said rib.
3. In a grader, the combination of a blade, a landside consisting of vertically disposed webs arranged one above the other, a bracket secured to said webs and bridging the joint
55 between them, said bracket being provided at its upper and lower ends with laterally directed lugs, a vertically disposed rib on the rear side of the blade at the end thereof, a coupling yoke having a sleeve fitting between the lugs on the bracket and having end members disposed at opposite sides of said rib, a vertical pivot bolt inserted through the lugs of the bracket and through the sleeve of the coupling yoke, and a horizontally disposed pivot bolt inserted through the end members of the yoke
60 and the said rib.

4. In a grader, the combination of a blade, a landside, a bracing connection between the blade and the landside at the centers thereof, said connection having universal movement, and means for coupling the end of the blade with the end of the landside.

5. In a grader, the combination of a blade, a landside having a platform on its inner side, a bracket secured to the rear side of the blade, a fork pivotally attached to said platform, and a bracing yoke connected to the said fork for movement about a horizontal pivot and connected to said bracket for movement about a vertical pivot.

6. In a grader, the combination of a blade, a landside having a platform on its inner side, a vertically disposed bracket secured to the rear side of the blade and having rearwardly projecting lugs at its upper and lower ends, a bracing yoke having its ends disposed between the said lugs, a pivot bolt inserted through the ends of said yoke and the lugs at the ends of the bracket, a fork spanning the edge of the platform, a vertically disposed pivot bolt connecting the rear end of the fork with the platform, a stud at the front end of the fork extending through the rear end of the yoke and pivotally mounting the same, and means for retaining the yoke upon said stud.

7. In a grader, the combination of a blade, a landside, means for coupling the front end of the blade to the front end of the landside and effecting relatively vertical adjustment of the blade, and a bracing connection between the blade and the landside intermediate the ends of the blade and the landside said bracing connection permitting relative pivotal movement of the blade about a horizontal axis.

In testimony whereof we affix our signatures.
